COMBINATION WEATHER VANE, NAME PLATE
AND YARD ORNAMENT

Dale E. Doty, % Doty Manufacturing Company,
E. Platte Ave., Fort Morgan, Colo.

Filed Oct. 9, 1964, Ser. No. 82,120

Term of patent 14 years

(Cl. D35—1)

FIG. 2

FIG. 1 is a perspective view of a combination weather vane, name plate and yard ornament, embodying my new design; and

FIG. 2 is a front elevational view of the top portion with the remainder being omitted for convenience of illustration.

The dominant features of my design reside in the portion shown in full lines.

I claim:

The ornamental design for a combination weather vane, name plate and yard ornament, as shown and described.
